UNITED STATES PATENT OFFICE.

CLIFFORD H. OAKLEY, OF TRENTON, NEW JERSEY.

DESIGN FOR MATTING.

41,736.

Specification for Design.

Patented Aug. 29, 1911.

Application filed June 20, 1911. Serial No. 634,391. Term of patent 7 years.

To all whom it may concern:

Be it known that I, CLIFFORD H. OAKLEY, a citizen of the United States, residing at Trenton, in the county of Mercer and State of New Jersey, have invented a new, original, and ornamental Design for Matting, of which the following is a specification, reference being had to the accompanying drawing, forming a part hereof.

The figure is a plan view of a portion of a matting showing my new design.

I claim:

The ornamental design for matting as shown.

CLIFFORD H. OAKLEY.

Witnesses:

JOHN W. THOMPSON,
LUCIUS E. VARNEY.
